ASH TRAY

William F. Vernon, Sr., Newton, Iowa, assignor to The Vernon Company, a corporation of Iowa

Application May 4, 1959, Serial No. 55,771

Term of patent 14 years

(Cl. D85—2)

I claim:

The ornamental design for an ash tray, substantially as shown.
